UNITED STATES PATENT OFFICE.

MUNSON C. CRONK AND SIDNEY W. PALMER, OF AUBURN, NEW YORK.

IMPROVED WASHING-MACHINE

Specification forming part of Letters Patent No. 40,330, dated October 20, 1863.

To all whom it may concern:

Be it known that we, MUNSON C. CRONK and SIDNEY W. PALMER, of the city of Auburn, in the county of Cayuga and State of New York, have invented a new and Improved Washing-Machine; and we do hereby declare that the following is a full, clear, and exact description of the construction and operation of the same, reference being had to the accompanying drawings, making a part of this specification, in which—

Figure 1 represents a vertical sectional view, the divisions being made in the direction of the lines *d d*, Fig. 2. Fig. 2 is a top view of the same. Fig. 3 is a longitudinal view of the fulcrum. Fig. 4 is a bottom view of one of the ribs, showing its under side and the channel cut in it.

Like parts are lettered alike in the various views.

The nature of our invention consists in providing the kind of washing-machines commonly designated as "tub-machines," with, first, a lever to enable the operator to give the required pressure with a less outlay of strength and labor, and to operate the machine while standing erect beside it, instead of being obliged to lean over it in a laborious position and inhale the vapors rising from the suds; secondly, in providing the rotary rubber with hinged sections, which can be raised at pleasure for the purpose of examining the clothes without lifting it entire and removing it from the tub; thirdly, in providing for a freer circulation of the water by cutting water-channels in the under side of the bottom ribs and holes in the rotary rubber, said holes being in such positions relatively with the buttons which hold the hinged sections of the rubber in place, as that in the rotary motion of the latter the said buttons shall throw the surface water over and into said holes; fourthly, in providing a false bottom, so that when desired the washing apparatus may with little trouble or preparation be put into any ordinary wash-tub and removed at pleasure.

To enable others skilled in the art to make and use our invention, we will proceed to describe its construction and operation.

C is a false bottom, placed upon and covering the real bottom of the tub *A'*. Upon *C* are fastened the hollow or channeled radial ribs *a a*.

Fixed firmly into its center is the upright post *D*, and projecting from its lower surface and into holes bored into the bottom of the tub are the pins *c c*, for the purpose of preventing *C* from revolving with the rubber *B*. This false bottom *C* may be dispensed with, together with the pins *c c*, and the ribs *a a a* and upright *D* fastened upon and into the real bottom of the tub *A'*. The utility of *C* is merely to enable the completion of the washing apparatus so that it can be used in any ordinary tub, and so that it may be removed from the tub that the latter may be used for any other purpose. *B'*, with its hinged sections *B B*, are the rotary rubber. To its under side are fastened the radial ribs *a' a'*, corresponding in number and as nearly as may be in position with those already described on the false or real bottom. The sections *B B* are so hinged to *B'* as to leave an open joint or a space between them, as shown in Fig. 2, so as not to catch any portion of the clothes when the sections *B B* are dropped down to their place. Pivoted to the upper side of *B'*, or of the sections *B B*, are the buttons *P P'*, which, when extended as shown at Fig. 2, hold the hinged sections *B B* down to their place. Near the inner ends of the latter are the holes *h h*. The buttons *P P'* may be curved inward, so as more perfectly and powerfully to force the surface water inwardly and into the said holes at every motion to the left of the rubber. Fixed firmly to the rubber are the two uprights *G G'*. Into *B'*, upon either side of the hole through which passes the center post, *D*, and opposite to its center, are cut notches *S'* to receive the forked and beveled ends of the fulcrum *U*.

r is a spiral spring for the purpose of lifting the rubber *B* when pressure is removed from the latter.

H is a lever having cut into it at proper intervals the elongated holes *n n'* and slot *n''*, to receive the uprights *D* and *G G'*. The slot and elongated holes enable the lever *H* to be moved up and down easily, and its outer end to be considerably elevated or depressed without its binding upon either of the uprights. The hole *n'* is elongated in but one direction, that toward the handle *u*, its reverse side resting against the upright *D*. Into the under side of the lever *H* is cut the

notch S, to receive the single-beveled end of the fulcrum U.

L is a wooden collar passing freely over the upright D. Its purpose is to transmit the resistance of the pin O to the lever H with uniformity.

O is an iron pin fitting into either of the holes e e and acting as a resistance to the upward tendency of the contiguous section of the lever H when pressure downward is applied at u.

e e are a series of holes in the upright D to receive the pin O, and are thus numerous to accommodate different quantities of clothes.

t' is a pin projecting from the upright D to support the rubber while the clothes are turned over or placed in or removed from the tub.

t is a recess or slot cut through the rubber B and opening into the hole by which the post P passes through the rubber B. The purpose of t is to enable the rubber to pass freely over the pin t'.

U is a fulcrum by which the pressure downward applied at u is transmitted to the rubber, increased in the same ratio that the distance from u to S is greater than the distance from S to L.

The operation of this apparatus is as follows: The clothes, with a proper proportion of soap and water, are placed in the tub, the rubber and superincumbent parts having been removed. The latter are now replaced and the machine arranged as in Fig. 2. The operator grasps the lever H at u and oscillates it from right to left and left to right horizontally, making from an eighth to a quarter of a revolution. This backward and forward motion is communicated to the rubber by the uprights G G'. At the same time the operator applies a downward pressure at u greater or less in proportion to the celerity desired or the kind of fabric being operated upon. The weight of the hand, or a little more, is sufficient in most cases. The immediate action upon the clothes is to move them back and forward but only a small proportion of the distance traversed by the rubber B in its oscillating movement, rubbing them against each other and against the rubber and the bottom of the tub. But the principal action is as follows: Whenever a rib on the bottom and a rib on the rubber come into juxtaposition, the effect is to press or squeeze out a portion of the water from the intervening clothes. As the ribs leave this position, the same portion of fabric from which the water has just been expressed

is left at liberty to absorb the same again, and thus the process of expression and absorption goes continually on, and at as many points simultaneously as there are opposing ribs upon the rubber and bottom board. Occasionally the pressure will be removed from the lever H, and the rubber is immediately lifted from the clothes by the action of the spring r, and while in this position the lever may be carried around to another quarter, the pressure again applied, and the process continued. The tendency of this rotary oscillating motion is to throw the water from the center to the circumference, leaving the center but poorly supplied. To obviate this serious difficulty channels are cut in the under side of the bottom ribs, as shown in Fig. 4, through which the water can be returned to the center. Likewise the action of the buttons P P' is such as in the leftward motion of the rubber to throw the water into the holes h h. To facilitate this flow of water through the channels in the lower ribs passages may be cut at different points along the under surface of the rib connecting this channel with the space outside, as shown at f, Fig. 4. To examine the clothes one or both of the hinged sections may be raised by turning the buttons P P' so that they occupy the position shown by dotted lines at b, Fig. 2. When the clothes are to be removed or turned over, the fulcrum U is removed and the rubber lifted above the pin t', when a partial revolution will enable it to rest on said pin, when the clothes can easily be removed or turned over. The ribs may be made with parallel sides or with a slight taper. In the latter case those on the bottom board will have their large ends opposed to the small ends of those on the rubber.

Having thus fully described our invention, we would say that we do not claim as new the rotating rubber with the accompanying radial ribs; neither do we claim any outside form of the ribs or any particular arrangement of the same; but

What we do claim as new, and wish to secure by Letters Patent, is—

The fulcrum U, the lever H, the collar L, the ribs a a, the buttons P P, the hinged sections B B, the false bottom C, and the upright D, the whole constructed and arranged substantially as herein set forth.

M. C. CRONK.
